UNITED STATES PATENT OFFICE

ROBERT GOFF, JR., OF KANSAS CITY, MISSOURI, ASSIGNOR OF ONE-HALF TO JOHN HOLLMAN, OF KANSAS CITY, MISSOURI

CREAM-PUFF-FILLING MACHINE

Application filed May 25, 1929. Serial No. 366,060.

This invention relates to the class of pastry making and pertains particularly to a machine design to facilitate the introduction of cream into puff pastries or for the introduction of other fluids or semi-fluids into bodies of pastry.

The primary object of the present invention is to provide a machine by means of which measured quantities of cream or paste may be injected into pastry shells or puffs by forcing these measured quantities at regular intervals through nozzles, the outlet ends of which are formed to facilitate their extension into the body of the pastry.

The invention broadly contemplates the provision of a receptacle having one or more pipes leading therefrom through a check valve and to a pipe opening at one end into a cylinder and at the other end into the paste or cream injecting nozzle, a one-way valve being interposed between the rear end of the nozzle and the end of the pipe with which the nozzle connects to prevent air from being sucked into the machine through the nozzle during a period in the operation of the machine.

Reciprocably mounted in the cylinder is a piston member which is actuated by an oscillating arm carried by an oscillating shaft, which in turn is actuated through a system of shafts and connections by a suitable power element such as an electric motor. The operation of the motor causes the piston to reciprocate at a regulated speed and at each idling stroke the piston draws paste from the receptacle through the first mentioned one-way valve and upon the power stroke ejects the paste through the second mentioned valve and through the nozzle into the pastry body into which the outlet end of the nozzle has been extended.

The invention will be best understood from a consideration of the following detailed description taken in connection with the accompanying drawings forming a part of this

specification, with the understanding, however, that the invention is not confined to any strict conformity with the showing of the drawings but may be changed or modified so long as such changes or modifications mark no material departure from the salient features of the invention as expressed in the appended claims.

In the drawings:—

Figure 1 is a view in front elevation of the machine embodying the present invention;

Figure 2 is a top plan view of the forward portion of the machine looking down upon the material ejecting cylinders;

Figure 3 is a sectional view taken substantially upon the line 3—3 of Figure 1;

Figure 4 is a detailed sectional view taken longitudinally of one of the cylinders.

Referring more particularly to the drawings, it will be seen that the machine embodying the present invention has been shown as mounted upon an open frame structure which is indicated as a whole by the numeral 1, this frame being preferably mounted upon castor rollers 2 to facilitate its being shifted from one place to another.

It is, of course, to be understood that the frame structure shown is one form which may be employed and I do not wish to be limited in any manner to the use of a frame or body structure of this character, as it is obvious that other means may be employed for supporting the mechanism hereinafter described, however, the detailed structure of the frame shown will be described for the sake of clearness in connection with the description of the mechanism which it carries.

The frame 1 comprises a base portion 3 of generally rectangular formation, and uprights 4, one at each corner of the base, and a top frame 5 of similar construction to the base 3.

Mounted upon the base 3 is a power unit, preferably an electric motor 6, the shaft 7 of which connects with a speed reducing mech-

anism 8, of any desirable construction, which mechanism is in turn connected through the meshed gears 9 and 10 with a horizontal shaft 11 rotatably supported between the spaced upright members 12.

The shaft 11 carries at one end a crank 13 to which is connected an arm 14 designed to reciprocate transversely of the frame structure, in the manner shown.

10. The end of the arm 14, remote from the crank 13, carries a pin 15 which is adjustably secured in the slot 16 formed longitudinally in the lower end of a normally vertically arranged rock arm 17 traversed intermediate its ends by a rock shaft 18, the ends of which are suitably mounted in the spaced upright members 19 carried upon the base 3 of the frame. Suitable adjustable collars 20 are carried by the rock shaft 18, at opposite sides of the rock arm to hold the same in adjusted position thereon.

15. The upper end of the rock arm 17 has pivotally secured thereto one end of a second reciprocating arm, which is indicated by the numeral 21, the other end of this arm being pivotally secured to the lower end of a second depending rock arm indicated by the numeral 22, carried by a main rock shaft 23. The arm 21 carries a pin 24, similar to the pin 15 carried by the arm 14, which pin is adjustably secured in a slot 25 formed longitudinally of the lower end of the rock arm 22, in the manner shown.

20. Any suitable means may be employed for mounting the ends of the main rock shaft 23, as for example, there may be provided at each end of the shaft a hanging bearing member 26 in which the end of the shaft may position.

25. Mounted upon the top portion 5 of the frame structure in spaced substantially parallel relation is a pair of piston cylinders, each of which is indicated by the numeral 27. To the forward end of each of these cylinders 27 is connected by means of a nipple 28, one arm of a three-way coupling 29, the opposite arm of each coupling having connected thereto a one-way outlet valve 30 to the opposite side of which valve the base portion of a tubular needle or nozzle 31 is connected.

30. The third or lateral arm of each three-way coupling connects with one side of an inlet check valve 32, the opposite side of which valve is in communication with the interior of a fluid receptacle 33 through the pipe line 34. As shown, the pipe line 34 connecting the receptacle with the one-way inlet valve 32 enters the receptacle through the bottom and assists in the support thereof.

35. Extending into each of the cylinders 27 through the other or rear ends thereof is a piston 35, having a rod 36 connected thereto, each of said rods having pivotal connection as at 37, with one end of a connecting arm 38, the other end of which arm is secured to the main rock shaft 23 to be rocked therewith.

From the description given it will be readily seen that in the use of the present machine, when the motor 6 is started, the arms 17 and 22 will be rocked back and forth and cause the rocking of the shaft 23 and the arms 38 connected thereto.

40. The rocking of the arms 38 will cause reciprocatory movement of the pistons 35 and upon each backward movement of each piston, a predetermined quantity of the cream puff filling material will be sucked into the cylinders through the inlet check valve 32 and upon the forward movement of each piston this same quantity of material will be ejected through the one-way outlet valves 30 and through the nozzles or needle 31 into the pastry body into which the free end of the needle 31 has been extended.

45. In any suitable position upon the upper portion of the frame 1, there may be mounted a control switch 39 for the motor, connection being made between the switch and the current supply line for the motor through the cabled current wire carrying line 40.

50. From the foregoing description it will be readily seen that with a machine of the character herein described cream puffs and other articles of a similar nature may be more rapidly filled than by the employment of methods at present in use and further, exactly the same quantity of material will be ejected into each body of pastry. It is, of course, obvious that by the adjustment of the connections between the reciprocating arms 14 and 21 and the oscillating or rocking arms 17 and 22, the throw of the piston controlling arms 38 may be increased or decreased to increase or decrease the quantity of material ejected through the nozzles 31 and by the use of a suitable control rheostat the speed of the motor 6 may be regulated as desired.

55. Having described my invention, what I claim is:-

1. A machine for injecting liquids into pastries, comprising a supporting frame, a pair of pumps mounted upon the frame and each including a cylinder and a piston, a liquid receptacle, a pipe line extending from one end of each of said cylinders, the axis of said pipe line being coplanar with the axis of said cylinder, a nozzle associated with each pipe line, a check valve interposed between each nozzle and the adjacent cylinder, a lateral pipe line connecting each of the first mentioned pipes between the check and the cylinder with the receptacle, a check valve in each of said lateral pipes, and power operated means for reciprocating each of the pistons of said pumps.

60. 2. A machine for injecting liquids into pastries, comprising a supporting frame, a pair of pumps mounted upon the frame and each including a cylinder and a piston, a liquid receptacle, a pipe line extending outwardly and concentrically from one end of

each of said cylinders, a nozzle associated with each pipe line, a check valve interposed between each nozzle and the adjacent cylinder, a lateral pipe line connecting each of the first mentioned pipes between the check and the cylinder with the receptacle, a check valve in each of said lateral pipes, a power unit mounted upon said frame, means connected with said power unit for converting 10 rotary motion to oscillatory motion, and means for employing said oscillatory motion to reciprocate the pistons of said pumps.

In testimony whereof I hereunto affix my signature.
